VERNIER ADJUSTMENT.

Application filed December 22, 1924. Serial No. 757,391.

The present invention relates to means for securing fine angular adjustment of a rotary shaft, or the like.

In the operation of the tuning coils and condensers of a radio outfit, angular adjustments of extremely small extent are often found desirable after the general position of the rotary part has been determined upon. Such means for minute adjustment are often

10 called vernier adjustments.

We are aware that numerous schemes have been proposed for securing vernier adjustment, but so far as we are aware, they have not been satisfactory, chiefly because they 15 have undesirable back lash, have yielding parts which soon cease to function, are not positive in operation, and because they deface the panel, or have such projecting or protruding unsymmetrical parts as spoil the 20 neat appearance of the instrument.

According to the preferred form of the present invention, we provide a vernier adjustment which is neat and attractive in appearance, does not require separate mounting 25 on the panel, gives a fine adjustment with a relatively large leverage, and contains no appreciable lost motion. Furthermore, all the necessary parts may be mounted on the dial itself and they require no separate 30 mounting upon the panel.

According to the preferred form of the invention, we provide a shaft to be adjusted with a loose dial and an arm which may be a supplementary dial, if desired, which arm is fixed on the shaft. We connect these 35 parts, namely, the loose dial and the fixed arm with a lever or crank which is adapted to swing across the face of the loose dial. Now we may hold the loose dial by hand or by a clamp to the panel, if desired, and then 40 operate the crank lever to secure relative angular adjustment of the shaft with respect to the dial, or vice versa. The ratio of the crank arm to the connecting arm may be 45 adjusted to any desired ratio within limits, so that an extremely fine adjustment of the shaft may be secured.

In the preferred form of the invention, we 50 operate the crank arm by a sliding element which moves on a diameter of the main dial.

This sliding element is so constructed that in its operation the operator may not only move it along the diameter of the main dial, but may, at the same time, resist any tendency of the main dial to rotate, thus holding

it stationary at its set point while the secondary dial or arm is caused to rotate, thus rotating the shaft within the main dial. This, in effect, makes the main dial, for the purpose of this secondary motion, the equivalent of the panel upon which the instrument is mounted, as it is intended that it shall, during that secondary motion, be held immovable with respect to the panel.

As previously stated, this primary dial 65 may be held immovable with respect to the panel in several ways; by holding it with one hand while the secondary movement is effected by the other hand, by holding it stationary with certain fingers of one hand 70 while the secondary movement is effected by movement of another finger or fingers of the same hand, by a direct contact with the panel, or by the manner of construction shown whereby the very manner of applying 75 the secondary force along the diameter of the main dial resists a rotation of the main dial while the secondary dial is being rotated.

This latter arrangement tends to minimize 80 or practically eliminate any rotary effort upon the dial and eliminates the necessity for the soft contacts between the main dial and the panel. We consider this feature to be a valuable part of the invention.

In the modified form of our invention, the 85 crank, instead of being connected to the loose dial and the loose dial to the panel, may be moved into engagement with the panel directly and then swung across the face of the 90 arm or dial which is connected to the shaft.

Now, in order to acquaint those skilled in the art with the manner of constructing and operating our invention, we shall now describe a specific embodiment of the same in 95 connection with the accompanying drawings.

In the drawings:

Figure 1 is a face view of a device embodying my invention;

Fig. 2 is a vertical section taken on the 100 line 2-2 of Fig. 3;

Fig. 3 is a horizontal cross section taken on the line 3-3 of Fig. 1;

Fig. 4 is a fragmentary section taken on the line 4-4 of Fig. 2 and showing the adjustable pivot for the control arm;

Fig. 5 is a fragmentary sectional view taken on the line 5-5 of Fig. 2;

Fig. 6 is a fragmentary section of a modified form of the device, in which clamping

85

means is provided for clamping the loose dial to the panel;

Fig. 7 is a face view of a modified form;

Fig. 8 is a vertical section taken on the line 8—8 of Fig. 7;

Fig. 9 is a horizontal cross section taken on the line 9—9 of Fig. 7;

Fig. 10 is a front view and

Fig. 11 is a vertical section of another modification;

Fig. 12 is a face view; and

Fig. 13 is a vertical section of a further modification.

In the drawings, we have shown the panel 1, which is made of insulating material and which forms a front part of the housing, within which the parts to be adjusted are contained. In the present instance, the shaft 2 projects through an opening 3 in the panel 1, and this shaft is adapted for rotary or oscillatory motion. The front end of the shaft 2 projects through the panel 1, and it has fastened thereupon a sleeve 4, having a collar or flange 5 at the rear. A secondary sleeve 6, which has an arm 7 extending therefrom, is fastened upon the front end of the sleeve 4, as by means of the screw 8, which passes through both sleeves 4 and 6 and secures them to the shaft 2. Between the rear end of the collar 6 and the flange 5, we mount the loose dial member 9 which thus has a bearing upon the sleeve 4. The arm 7, which is thus fast to the shaft 2, has an adjustable yoke or collar 10 thereupon, this yoke or collar having a lug 11 forming a pivot for the lever arm 12, which extends therethrough. At its rear end the lever arm 12 is pivoted at 13 to the dial 9, so that movement of the free end of the lever about said pivot 13 tends to swing the free end of the arm 7 about the axis of the shaft 2 and to oscillate or rock said shaft 2. At its forward end the lever or crank 12 is pointed or suitably fashioned at 14 to form an indicating finger playing over a scale 15 on the dial 9.

In order to guide the crank arm and indicator 12, 14, we provide a guide member 17 which, in the present case, is formed of a flat piece of bar lying on a major diameter across the axis of the shaft 2, and forming a guide for a slider or collar 18, this collar having a lug 19 through which the crank or lever arm 12 passes.

The collar 18 is intended to fit snugly on the guide member 17 and to have side contact along the guide member 17 for a sufficient distance on both sides to enable the operator, when sliding the said collar along said guide member, to resist a sidewise movement of the guide member 17 and hold it in a fixed position while the collar is being moved along it. The exact amount of side contact to be applied under various conditions will depend upon the conditions

themselves and becomes a matter of mere practical adaptation to the particular conditions.

On its front side the slider or collar 18 has a finger piece or knob 20 by which the slider 18 may be moved back and forth upon the guide 17. The ends of the guide are bent down and form attaching feet, as indicated at 21, for securing the same to the face of the dial 9.

The openings through the lugs 11 and 19 are counterbored with a conical taper on each side so that the round arm or crank 12 may have angular motion therein without binding. If desired, a post having a cylindrical opening and pivoted on the member 10 or 18 may be substituted instead. This is within the skill of those familiar with the art.

The operation of the device is believed to be obvious from the above description. The dial is moved to any desired angular position, the slider 18 affording sufficient friction to prevent relative motion between the arm 7 and the dial 9 when the dial is moved, to move the shaft 2. It will be understood that the arm 7 may be formed as a supplemental dial, if so desired, or a knob or projection provided to permit convenient grasp by the fingers.

When the desired general angular position is reached, then the vernier mechanism is called into play and, by moving the finger piece 20 back and forth along the guide 17, a relative motion between the arm 7 and the dial 9 is secured. We may hold the dial 9 by means of one end while the other is employed to adjust the vernier mechanism or, under certain circumstances, the rotative component on the dial 9 may be counterbalanced by the force of the hand in moving the finger piece 20.

In Fig. 6 we have indicated a modification in which the dial 9 may be clamped to the panel 1, while the vernier mechanism is operated. In this case we provide a small clamping lever 25, the outer end of which forms a convenient socket or holder, as indicated at 26, for holding the forward end 14 of the arm 12, this clamping arm 25 being positioned preferably at the zero position of the vernier mechanism. At its inner end the lever 25 has a friction foot or surface 27, which may be of rubber, or the like, for clamping the dial 9 against the panel 1, this lever being pivoted in the dial 9, as indicated at 28. The operation of this form of the device will be apparent. The parts are tied together through the lever 26 and the end of the arm 14, so that no relative motion between the dial and the arm is permitted during the normal position of the parts, as indicated in Fig. 6, and therefore, the shaft 2 may be readily adjusted. Then, when the general position is attained, the lever 25

is swung about in a clockwise direction, as viewed in Fig. 6, to clamp the dial 9 to the panel 1 and to release the indicating lever 12. Then the lever 12 may be swung back 5 or forward to secure the desired vernier adjustment of the shaft 2 to the crank arm or leverage provided between the pivots 11 and 13.

In Figs. 7, 8 and 9, we have indicated a 10 modification in which the lever is pivoted upon the member that is secured to the shaft 2, and instead of operating through the dial member 9 and then to the panel 1, we make the outer end of the lever engage the panel 15 directly. In said device, we have the panel 1 and the shaft 2, as previously described. On the shaft 2 we mount a dial member 30 which has an extending hub 31 containing a metal insert 32 fastened to the shaft 2, as 20 by means of the set screw 33. At its central portion this dial 30 contains a socket 34 containing a plurality of spring arms for engaging the button 35, which button is the head of a screw. The screw 35, which is 25 adapted to enter and snap into the socket 34, passes through a lever 36 and into a metal insert 37 in the finger piece or button 38, which button or finger piece is thus mounted upon the lever 36, and when the 30 lever 36 is in its central or neutral position, this button 38 lies axially in line with the shaft 2. The lever 36 has a pointer 39 at its free end playing over the scale 40 on the dial member 30.

The lever 36 is pivoted at 41 in a post 42, which post is set in a recess in the dial 30 and is held between a shoulder 43 and the head 44 of a screw for holding the post in the dial. A spring washer 45 may be inserted 40 between the head and the shoulder adjacent the same.

The post 42 therefore is adapted to swing about a horizontal axis in the dial 30. The lever 36 is adapted to swing about a vertical axis in the post 42 (as viewed in Fig. 7). At its rear end the lever 36 has a clamping foot 46, which is adapted to engage the panel when the button 35 is withdrawn from the socket 34.

50 The operation of the device is as follows: Assuming that the parts are in the position shown in Figs. 7, 8 and 9, the finger piece 38 is rigidly connected to the dial 30 by the button 35 and spring socket 34, and 55 also by the fact that the finger piece is connected to the lever 36, which lever is secured to the post 42. Therefore, by turning the finger piece 38, the shaft 2 may be turned to any desired position until a coarse adjustment is secured. Then the button 35 is withdrawn from the spring socket by 60 swinging the finger piece outwardly from the dial about the pivot 41, this resulting in engagement of the foot 46 with the panel 1, under the influence of the spring 47, which

is mounted upon the post 42. The spring 47 maintains sufficient tension upon the foot 46 as to connect these parts together, so that the button 38, with its attached lever 36 and pointer 39, may be swung laterally to secure 70 a cranking or twisting action about the foot 46 which then serves as a stationary pivot to move the post 42, which is then the movable pivot, and thereby to move the dial 30 and the connected shaft 2 to the desired vernier 75 adjustment.

The device shown in Figs. 7, 8 and 9 may be operated by omitting the snap in the socket 34. In this manner the foot 46 is normally in contact with the panel and, therefore, the dial is set for the fine adjustment 80 when in the normal position. By pressing inward on the button 35 and holding it so the foot 46 will be lifted from the panel and permit free movement of the entire dial 85 until the pressure upon the button 35 is released, when the foot 46 will come again into contact with the panel and the dial will be again in its normal position.

It will be seen that this device may, therefore, be adapted to make either condition 90 the normal condition as desired.

In the modification shown in Figs. 10 and 11, the shaft 2, which extends through the panel 1, is secured in a disc 50 preferably 95 formed of molded insulating material and having a metal collar inserted therein, as indicated at 51, for mounting the clamping screw 52 to connect said disc 50 to the shaft 2. The disc 50 has a pair of shoulders 53 100 between which lies the rear or longer arm 54 of the lever 55. The shorter arm 56 forms a pointer at 57 which is adapted to co-operate with the scale formed on the indicating ring 58, which indicating ring 58 preferably 105 has a central web or disc 59 providing a roughened surface 60, adapted to co-operate with a pivot or foot 61 formed on the lower side of the short arm 56. This foot piece 61 is preferably formed of insulating 110 material and there is a rubber cap or a rubber insert at its lower end for giving a relatively yielding contact with the roughened surface 60, which roughened surface 60 is preferably knurled. The foot 61 has a metallic eyelet 62 molded therein, and this is riveted over the edge of a hole in the arm 56.

The disc 50 has a shallow radial recess to receive the flexible spring member 63, which is mounted in said seat by means of a metallic eyelet or rivet 65 at its inner end for holding said spring in the seat and at its outer end is attached to the lever 55 by means of a similar eyelet or hollow rivet 66. At its rear end the lever 55 bears the 120 operating handle or knob 67 by which the lever and shaft are moved. The operation of this form of the device is as follows: When the parts are in the position shown, the lever 55 has its rear end 54 lying between 125

the shoulders 53 and the shaft 2 may be moved in an angular adjustment by means of said knob 67 which forms a crank for moving the shaft 2 to the desired general position. As soon as it is desired to operate the vernier mechanism, the knob or handle 67 is pulled away from the disc 50 to disengage the rear end of the lever 54 from said shoulders 53, and at the same time, by bending 10 the spring 63 to bring the foot 61 into engagement with the roughened surface 60. By this action, the lever 55 is connected at its remote end to the stationary panel and at its intermediate end through the eyelet 15 66 to the disc 50, this eyelet serving as a pivot so that as the handle 67 is now moved in an angular direction, the shaft 2 no longer partakes of the same degree of motion, but takes only the greatly reduced motion 20 corresponding to the length of the lever arms 56 and 54. Obviously, instead of having the disc 59 interposed, the foot 61 may engage the panel 1 directly.

In the form shown in Figs. 12 and 13, 25 substantially the same mechanism is employed. In this case, however, the disc 70 extends beyond the foot member 61' and carries on its sloping surface 71 the graduations for indicating the position of the shaft 2. 30 In this case, the short arm 56' is not employed for indicating purposes, but is employed solely for depressing the foot 61' and rocking the disc 70 to and fro, as may be desired. The foot 61' projects down 35 through the disc 70, a suitable slot 72 being provided to permit lateral motion of the pin or foot 61' with respect to the disc 70. The foot 61' may be merely a pointed sheet 40 of metal which may engage the surface of the panel 1 and, since this portion of the panel is completely covered, scratching or marring of the surface at this point will not be noticeable.

The operation of this form of the device 45 is substantially identical with the form just previously described, that is to say, the handle 67, which is formed of insulating material and which is fastened by means of the hollow eyelet or rivet 73 to the lever 55, 50 is normally held to the disc 70 by means of the shoulders 53 so that movement of the handle or finger piece 67 imparts its proper motion to the disc 70 and hence to the shaft 2. By this means the disc 70 may be swung 55 about the desired angular position. When substantially the position desired is attained, the knob or handle 67 may be pulled outwardly away from the panel 1 to release the lever 55 from the shoulders 53 and, at 60 the same time, to bring the foot or pin 61' into engagement with the panel 1 to connect the remote end of the lever to the stationary panel. Then, by rocking the lever about the pivot 66, the disc 70 partakes of the limited 65 degree of motion corresponding to the short

lever arm 56'. In this form as well as in the foregoing form, the spring 63 serves the double function of permitting this light in and out rocking motion of the lever 55 to bring the foot 61 or 61' into engagement 70 with the stationary parts and when the knob or handle 67 is released, the spring 63 performs the function of bringing said knob or handle and its lever back into position against the disc 50 or 70, as the case may be. 75 When it is desired to resume motion of the disc 70, the knob 67 is moved over into neutral position and dropped between the shoulders 53, the spring 63 tending to hold the parts in such position. The edges of the 80 spring 63 lie between parallel shoulders which form a seat for said spring to prevent lateral motion of the same about its holding rivet 65. These shoulders, however, permit flexing of the spring in and out with 85 respect to the panel 1, in order to perform the function heretofore described.

We do not intend to be limited to the details shown or described.

We claim:

1. In combination, a fixed member, a shaft, a dial fixed on said shaft, a lever pivoted between said dial and said fixed member, the free end of the lever extending over the dial and forming an indicator 95 and a scale on said dial co-operating with said indicator.

2. In combination, a panel, a shaft, a member fixed on the shaft, a pivot on said member, a lever mounted on said pivot and 100 having its outer end connectible with the panel, said lever being movable across the end of the shaft substantially parallel to the panel.

3. In combination, a panel, a shaft projecting through the panel, a member on the front side of the panel, a pivot on said member, and a lever mounted on said pivot and adapted to have connection with the panel, 105 said lever having its free end pointed to form an indicator and a finger piece connected to the lever, said finger piece being adapted to lie axially in line with the shaft when the lever is in neutral position.

4. In combination, a panel, a shaft projecting therethrough, a dial on the front end thereof, a lever pivoted to the dial, said dial having graduations thereupon, and the end of the lever sweeping over said graduations and forming an indicator. 115

5. In combination, a shaft having a member secured thereto, a lever pivoted to the member, means for connecting the lever directly to the member for common angular motion and means connecting the lever to 125 the member for relatively reduced angular motion with respect to the lever, said lever comprising a foot member movable into engagement with a stationary abutment.

6. In combination, a shaft having a mem- 130

ber secured thereto, a lever pivoted for two degrees of motion with respect to the member, and means for holding the lever directly to the member for common angular motion.

5 7. In combination, a shaft, a member secured to the shaft, a lever mounted on said member, said lever having a foot member adapted to engage a stationary abutment, and said member having means for engaging the lever to hold the lever and the member together for common angular motion.

10 8. In combination a fixed member, a rotatable member extending therethrough, an arm fixed to the rotatable member, a lever member carried by said arm and adapted to make contact with said arm and said fixed member and, by its movement, to secure relative movement between said arm and

20 said fixed member.

9. In combination a fixed member, a rotatable shaft extending through said fixed member, a lever carried on said shaft and pivoted thereto, and means for connecting one end of said lever to the fixed member.

25 10. In combination a fixed member, a rotatable shaft extending through said fixed member, a lever carried on said shaft and pivoted thereto, and means for securing

relative motion between said fixed member and said shaft by making contact between said fixed member and one end of said lever and moving the other end of said lever.

30 11. In combination, a panel, a shaft projecting from the same, a head on said shaft, a vernier element carried by the head but normally out of contact with the same, said element having two degrees of motion with respect to the head, said vernier element 35 having a portion adapted to engage the panel by one degree of movement thereof and to shift the head with respect to the panel by the other degree of motion.

35 12. In combination, a shaft, a stationary member adjacent the same, a head on the shaft, a pivoted vernier element carried by the head out of contact with the member, said element having a portion adapted to be projected into engagement with the stationary member, and a handle for moving the element through a limited rocking movement to adjust the shaft with respect to the stationary member.

40 45 50 In witness whereof, we hereunto subscribe our names this 20th day of December, 1924.

JOHN A. DIENNER.
ALEXANDER C. MABEE.
